UNITED STATES PATENT OFFICE.

WILLIAM J. MERTEN, OF PITTSBURGH, PENNSYLVANIA, ASSIGNOR TO WESTINGHOUSE ELECTRIC & MANUFACTURING COMPANY, A CORPORATION OF PENNSYLVANIA.

CARBURIZING CONTAINER.

Application filed May 11, 1927. Serial No. 190,554.

My invention relates to the process of carburization and particularly to a self sealing carburizing container for holding the carburizing material and the metal objects 5 to be carburized.

In the carburizing process well known to the art the material to be carburized and the carburizer are placed in a metal container and covered by a metal cover or lid. It is necessary that the seal between cover and container be practically air-tight in order to prevent reaction with the oxygen of the air thus forming FeO and CO₂ and delaying the carburizing reaction.

Hitherto it has been the practice to seal the joint between the container and cover by luting the joint with clay or other refractory material. Such luting clays influence the cementation process unfavorably because they 20 contain oxide carrying materials which react with and consume the carbon of the carburizing material. Furthermore such a clay luting is likely to crack during the carburizing process thus providing channels by means of 25 which the carburizing gases may escape or the air may enter.

Therefore, it is among the objects of my invention to provide a container constructed entirely of metal and having a metal seal or 30 joint of a kind such that the cementation process will not be affected by the material used in making the joint.

Another object of my invention is to provide a container which will be practically air-tight and thus improve carburization.

A further object of my invention is to provide a container having a strong durable joint which is not readily subject to wear, whereby the same cover may be used repeatedly 40 without repair or replacement of parts.

Other advantages will become apparent in the following description of my device in which like numerals indicate like parts throughout the several figures:

Figure 1 is a sectional end view of my container.

Fig. 2 is a sectional side view of the container.

Fig. 3 is a top view of the copper gasket used in my device; and

Fig. 4 is an enlarged sectional view of my sealing device.

The container or box 1 may be a cast-iron box having its upper edge turned into a

U-shaped flange 2 on either two or three sides 55 thereof. The inside portion 3 of the U-shaped flange provides means for gripping or engaging the cover and gasket. The portion 4 of the U-shaped flange preferably extends over the opening in the box in order to provide a better seal between the cover and the container. However, if preferred the box 60 may be made of a special steel alloy and cut, shaped or welded in a manner well known to the art.

A sheet iron cover 5 is provided and this cover is preferably of the dimensions of the outside walls of the container so that it will 65 extend over the walls and engage the upper portion 4 of the U-shaped flange of the container.

A copper gasket 6, rectangular in shape is so proportioned that it rests on the seat 7 provided by the inner portion of the U-shaped flange. The inside dimensions are preferably 70 such that the gasket projects into the inside of the container.

The gasket 6 and cover 5 are slid into place 75 on the box from the unflanged end of the box. The thickness of the gasket and cover are 80 such that when they are in place on the box a close fit is secured at ordinary room temperature. The copper gasket engages the box so that the edge of the gasket just reaches the beginning of the circular portion 8 of the 85 turn of the flange. If desired the cover or the gasket or both may be slightly wedge shaped or the opening in the flange between the portion 4 thereof and the seat may be decreased from the front to the back of the box so that 90 when the cover is inserted, it will be wedged and a close fit will more easily be secured.

In the process of carburizing, the container 95 is heated from room temperature to a temperature of about 900° centigrade. The coefficient of expansion of copper is greater than the coefficient of expansion of iron. Therefore the combined thickness of the copper gasket and the iron cover will have increased more than the inside measurement of the U-shaped flange between the seat and the upper portion of the flange. (Dotted lines Fig. 4.) The horizontal dimension of the gasket also increases and consequently will be forced against the circular portion of the flange. 105 Therefore, a practically air-tight seal or joint will be formed when the box is at the carburizing temperature.

Because the joint is air-tight no air can reach the inside of the container and interfere with the carburizing process. Furthermore, a pressure slightly above atmospheric will be maintained within the container and result in accelerating, deepening and making more uniform the carburization of the parts.

Copper is chemically inert to the carburizing gas, and therefore does not interfere with or in any way affect carburization. The iron cover will become carburized but such action does not effect its utility nor effect the carburizing process.

After the carburizing process has been completed and the temperature of the container brought to room temperature the gasket, cover and box will have of course regained their former dimensions and the cover may then be easily removed.

20 The copper will of course have become ductile but its utility will not be affected since carburizing gases have little or no effect on copper. Therefore, the gasket may be used repeatedly until it has become so worn that 25 it will no longer be effective as a seal.

When several containers are to be used the inside dimensions of the U-shaped flanges 2 may be made smaller in successive containers so that when a gasket becomes too thin for 30 one container it may be used on a container having a decreased inside dimension of the U-shaped flange. Another means for taking up wear is to insert wedges at points 9 between the upper portion 4 of the flange 2 and 35 the cover 5.

It is apparent that modifications of my device will suggest themselves to those skilled in the art. For example, the cover may be provided with the U-shaped flange and the box 40 with the engaging flange. Although I have described a specific modification of my device I do not wish to be limited to the modification shown since other modifications of my device 45 may be made without departing from the spirit and scope of my invention as defined in the appended claims.

I claim as my invention:

1. A carburizing container comprising a box member having an opening in one side 50 thereof, a cover member, a plurality of U-shaped flanges extending over the opening, said flanges being disposed to form a seat for said cover member, and a metal gasket of material having a greater coefficient of expansion than the material of the flanges disposed 55 between said cover member and said flanges.

2. A carburizing container comprising a box member having an opening in the upper side thereof, a cover member, a U-shaped flange member on three sides of said opening 60 so disposed as to form a seat for said cover member, and a metal gasket having a higher coefficient of expansion than the material of the flange disposed between said cover member and a portion of said U-shaped flange for 65 the purpose of sealing the cover to the flange when heated.

3. A carburizing container comprising a box member having an opening in one side thereof, a cover for said opening, a flange on 70 the box member for engaging said cover and a gasket of a material having a higher coefficient of expansion than the material of the flange disposed between said cover and said flange whereby said cover will engage said 75 flange by reason of the expansion of the materials of said members when they are heated.

4. A carburizing container comprising a box member having an opening in one side thereof, a cover for said opening, a flange on 80 the box member for engaging said cover and a gasket disposed between said cover and said flange, said gasket having a greater coefficient of expansion than said cover and flange, whereby said gasket and cover will be tightened 85 in said flange when the carburizing container is heated.

5. A container comprising a box made of a material having a positive coefficient of expansion when heated, a cover member and a 90 gasket having a greater positive coefficient of expansion, a U-shaped flange on said box for engaging said cover and gasket, for forming a seal with said cover when they are heated.

6. A metal seal comprising a U-shaped flange consisting of metal having a positive coefficient of expansion, a seat in said flange, a cover member for engaging the seat and a gasket consisting of metal having a greater 100 positive coefficient of expansion than said first named metal, said gasket being mounted on said seat so that it will be tightened between said flange and cover when heated.

In testimony whereof, I have hereunto subscribed my name this 2nd day of May, 1927.

WILLIAM J. MERTEN.
